UNITED STATES PATENT OFFICE.

EDWARD AUGUST KOOP, OF LOUISVILLE, KENTUCKY.

BOTTLE-STOPPER.

1,165,422.

Specification of Letters Patent. Patented Dec. 28, 1915.

Application filed July 25, 1914. Serial No. 852,973.

To all whom it may concern:

Be it known that I, EDWARD AUGUST Koop, a citizen of the United States, residing at Louisville, in the county of Jefferson and State of Kentucky, have invented certain new and useful Improvements in Bottle-Stoppers, of which the following is a specification.

My invention relates to improvements in bottle stoppers, and has particular reference to improvements in bottle stoppers of the type which seals the bottles against the entrance of liquid or any other substance.

One of the objects of my invention is to provide an improved device of this character which will be simple, durable and reliable in construction and effective and efficient in operation.

Other objects of my invention will appear hereinafter.

Referring to the accompanying drawings: Figure 1 is a view in elevation of the neck portion of a bottle or receptacle sealed by an improved stopper embodying my invention. Fig. 2 is a vertical section through the stopper and neck of the bottle. Fig. 3 is a transverse section on the line 3—3 of Fig. 2, and Fig. 4 is a transverse section on the line 4—4 of Fig. 2.

In the drawings, which illustrate one embodiment of my invention, I have shown a stopper or closure device adapted to be inserted in the neck or opening of a bottle or receptacle for the purpose of permitting the original contents of the bottle to be removed and for preventing the refilling of the bottle.

In Figs. 1 and 2 I have shown the neck portion A of a bottle of usual construction, and this may be regarded as representative of any type of bottle desired to be used. This bottle, of course, has a hollow tubular shaped neck communicating with the interior of the bottle and open at its upper end. In the upper end portion of the bottle the stopper B is inserted for sealing the neck opening against the entrance of fluid or liquids into the bottle. This stopper may be of any suitable construction for the purpose. In the drawings I have shown one form of stopper of this kind. This tubular member or stopper has a continuous passage extending throughout its length and open at both ends. The lower end 2 of this passage communicates directly with the interior of the neck and thence to the interior

of the bottle. The upper end portion 3 of this passage is constructed so as to receive a cork 4. Between the upper and lower end portions 3 and 2 of the passage the passage is enlarged in diameter to form two chambers 5 and 6 which communicate with each other through a port 7 which is of less diameter than the diameter of the chambers and is formed by means of an annular internal rib or flange 8. These chambers 5 and 6 are occupied by check valves 9 and 10 respectively and these valves are constructed so they have some play within their respective chambers. They are constructed so that they serve to close the port 7 and the inner end 2 of the passage so as to prevent the entrance of liquid into the bottle. The seat for the upper valve 9 is formed by the internal flange or rib 8 while the seat for the lower valve 10 is formed by the internal rib or flange 11 which forms the inner or lower end 2 of the passage through the stopper. These valves are loose and free in their respective chambers but when the bottle is set upon its bottom in normal position the valves seat themselves by the action of gravity and any attempt to pass liquid or push the stopper into the bottle will be prevented by said valves.

When, however, the bottle is turned in a position to pour liquid from the bottle, gravity and the flow of liquid from the bottle act to unseat the valves and thereby permit the liquid to pass through the passage of the stopper. In the construction shown the stopper or tubular member 1 and the valves 9 and 10 are preferably made of some hard compact and solid material, such as porcelain or glass. The stopper is enlarged in diameter at its upper end or head to form a flange or shoulder 12 which abuts the end of the neck of the bottle and prevents the stopper from being forced into the bottle. In the construction shown it is customary to fill the bottle with liquid, insert the stopper B in the bottle, place the cork 4 in the upper end portion 3 of the stopper passage and then firmly securing or fastening the stopper in the neck of the bottle so that it cannot be removed and thus open the neck of the bottle.

In order to prevent unscrupulous persons from removing the stopper and using or refilling the bottle after its original contents have been removed, I provide means for interlocking the neck of the bottle and

stopper in such manner that the stopper cannot be removed without breaking the bottle, which, of course, renders the entire bottle useless. I provide an internal annular groove 18 in the neck of the bottle and a similar groove 19 in the periphery of the stopper member B. These two grooves or recesses are adapted to register when the stopper is inserted in its proper position in the neck of the bottle. In these registering grooves or recesses I provide a ring or annulus 20 of metal. This member 20 is in the form of a split ring and is made of spring metal. It is adapted to expand into a groove 18 in the neck of the bottle but this groove 18 is sufficiently deep so that part of the ring occupies the groove 19 in the neck of the stopper member B. Thus it operates to interlock the stopper and neck of the bottle in such manner that the stopper cannot be removed except by breaking the neck of the bottle, and of course once the neck of the bottle is broken the bottle is rendered useless. In assembling these parts the split spring ring 20 is placed in the groove 19 of the stopper member B and compressed or contracted in diameter so that it and the stopper may be forced into the neck of the bottle and as soon as the two grooves 18 and 19 register the ring will expand of its own elasticity and occupy the position shown in Fig. 2, thereby locking these parts.

In the drawings the locking ring 20 is shown as being circular in section and the grooves 18 and 19 correspondingly formed but it is obvious that this ring may be of any suitable shape in section and the grooves 18 and 19 of corresponding shape.

In order to seal space between the stopper B and the neck of the bottle I reduce the lower portion of the periphery of the stopper so as to provide a comparatively large space between the interior surface of the neck of the bottle and the stopper and in this space I provide a packing 17. This may be of any suitable substance for the purpose. I prefer, however, to use cork. The cork may be in the form of a single ring of sufficient height or it may be of a number of smaller rings, as shown in Fig. 2, so that the gasket or packing will be laminated, in a sense. This effectively seals the space between the stopper and the neck of the bot-

tle, and it will also be noted that since it is below the metal locking ring 20 it prevents any of the liquid within the bottle from coming in contact with the ring 20. This is important for the reason that in cases of some products, such as whiskies or wines, contact with metal acts to discolor the liquid or often destroys the flavor. The gasket or packing 14 therefore entirely obviates any possibility of such occurrence.

It will be obvious to one skilled in the art that my invention is capable of modification without departing from the spirit and scope of the invention.

What I claim is:

In combination, a tubular bottle neck of uniform bore, an integral tubular stopper having a cylindrical portion adapted to closely fit the interior of said bottle neck at the outer end thereof and an inner cylindrical portion of smaller diameter than the interior of said neck, packing material surrounding said smaller portion and filling the space between said portion and said bottle neck, a flange secured to the upper portion of said stopper and arranged to contact with the end of said bottle neck and overlie the line of contact between said stopper and said neck, a groove extending around said stopper and located below said flange and above said smaller cylindrical portion of said stopper, a groove extending around the interior portion of said bottle neck and positioned to register with said first-mentioned groove when said flange rests in place on the end of said neck, a spring ring surrounding said stopper and lying partially in each of said grooves, and a gravity valve within said stopper arranged to be inaccessible when said stopper is in place and to close the opening in said stopper when said bottle is in upright position, but to permit flow of liquid through said opening when said bottle is inverted.

In testimony whereof I have signed my name to this specification, in the presence of two subscribing witnesses, on this 22d day 100 of July A. D. 1914.

EDWARD AUGUST KOOP.
